UNITED STATES PATENT OFFICE.

GIANNI BETTINI, OF NEW YORK, N. Y.

METHOD OF RECORDING AND REPRODUCING SOUNDS.

SPECIFICATION forming part of Letters Patent No. 409,003, dated August 13, 1889.

Application filed April 11, 1889. Serial No. 306,812. (No model.)

To all whom it may concern:

Be it known that I, GIANNI BETTINI, a subject of the King of Italy, and a resident of New York, in the county and State of New York, have invented certain new and useful Improvements in Recording and Reproducing Articulate or other Sound or Sounds; and I hereby declare the following to be a full, clear, and exact description of the invention, such as will enable others skilled in the art to which it appertains to make and use the same.

This invention relates to the recording and reproduction of sound.

15 The object is to record articulate speech and other sounds and reproduce them with great amplitude and distinctness.

With this object in view the invention consists in the method of recording sound or 20 sounds by setting up vibrations in a body by articulation or otherwise, taking the vibrations from the body at several points or places, communicating them to a common point or place, and causing a record to be made from 25 this common point or place.

The invention consists, furthermore, in the method of reproducing sound or sounds by causing any suitable record (whether produced as above or otherwise) to act at a 30 single point or place and from this point or place causing vibrations at several points or places of a body capable of vibration; and the invention consists, finally, in the method of recording and reproducing sound or 35 sounds by taking vibrations off a vibrating body at several points or places, communicating them to a common or central point or place, causing a record to be made from this common point or place, and then from this 40 record causing vibrations at a common point or place and communicating these to several parts of a body capable of vibration.

Otherwise stated, the invention consists in taking off vibrations produced by sound- 45 waves from the vibratory body at several points or places, and communicating them to a central point or place to make a record of such vibrations; furthermore, in setting up vibrations at several points or places in a 50 body capable of being vibrated from a record

and developing sounds—such as articulate speech—therefrom.

By experiment it has been ascertained that when by articulation or other cause of production impulses are imparted to a fluid— 55 such as air—and are conveyed to a substance capable of being vibrated the vibrations caused in the substance are practically uniform throughout. I have found that these vibrations can be taken off at several points 60 or places, be communicated to a common or central point or place by means of transmitters, and be impressed upon a yielding material, producing a record, so that when the same or a similar central or common point or object communicating with several parts of a body capable of vibration is passed over this record vibrations like those originally produced are set up at the several parts of this body, and, the vibrations from these parts being 65 imparted to the air, great amplitude results, with precision of form, giving great distinctness.

Any suitable instrumentalities which will perform the operations above outlined may 70 be utilized, and I do not intend, of course, to limit myself in this respect.

What follows will serve as an illustration of one means by which my invention may be carried into effect. 75

In the accompanying drawings I have illustrated a suitable apparatus for carrying out my invention.

The particular apparatus shown forms the subject-matter of an application filed on 80 April 13, 1889, Serial No. 307,087.

In the drawings, Figure 1 is an inverted plan view of a frame and diaphragm with four converging arms or conveyers. Fig. 2 is a sectional view of the same. Fig. 3 is an inverted plan of a frame and diaphragm with the converging arms or conveyers and showing three enlargements. Fig. 4 is a sectional view of the same. 85

In the drawings, A represents a frame carried and sustained in suitable position to move longitudinally with relation to a cylinder or other body capable of receiving impressions, or to be stationary with relation to a longitudinally-moving cylinder or body of 90 95 100

this kind. The mechanism employed for moving the cylinder or other body or for moving the frame need not be herein particularly described, as the same forms no part of the 5 present invention.

The frame contains a chamber one side of which is formed by any suitable body capable of receiving vibrations—such as a diaphragm B—preferably attached to the frame

10 in such manner that a practically air-tight joint is formed. On the exposed face of the diaphragm is arranged a spider C, which has a number of arms or conveyers c attached to or at several points or places on the dia-
15 phragm and converging to a common point c', where I place a projection with or without a small wheel, the projection being designed to receive vibrations from the diaphragm and impart them to a suitable body for making a record, and subsequently to traverse the record so made and impart the same or nearly the same vibrations to the diaphragm as those originally imparted, causing sound-waves corresponding to those originally produced.

20 While I have here described a production of a record as well as a reproduction therefrom, it is to be understood that I do not confine my new mode of reproduction to use with my new mode of production, since I may employ my new mode of reproduction with fine effects as to increased amplitude and distinctness in connection with any phonograph-record made—that is, act upon my common point and from this communicate vibrations to several points or parts of a diaphragm.

In order more perfectly to preserve the character of the vibrations set up in the diaphragm, I find it of advantage to construct the frame C of such rigid material that it has 25 the least possible amount of independent vibration, in order that no interference with the vibrations transmitted from the diaphragm to the common or central point or place shall take place. For this purpose I 30 find that arms or conveyers T-shaped in cross-section are effective. At the central or converging points of the arms I place any suitable device adapted to make the record upon a soft or yielding substance and to traverse 35 a record, or, afterward, to traverse the record so made without injuring it. I find that a wheel of some substance, preferably of agate or ruby in the nature of a jewel, and to which light or sticky particles will not adhere, is 40 particularly adapted for this purpose, as by 45 it the disadvantage of a cutting-tool or stylus from which false vibrations are liable to be

set up are avoided. By using a wheel contact may be made with the cylinder or other body directly at right angles to its axis, thereby causing more perfect and uninterrupted communication with the impression of the record. On the opposite side of the frame to that at which the diaphragm is placed I may attach a tube, and, if desired, I 55 may attach to this tube a funnel.

My method differs materially from that which results from the employment of a cup carrying a point, which cup is in contact with the diaphragm, and which vibrates in itself, being, in effect, the equivalent of two diaphragms, in that in my device the conductors are separated and do not form a chamber for air or other fluid, and hence no vibrations from such air or fluid are transmitted to them, and also having separate or independent points of contact no damping effect is produced.

Having thus fully described my invention, what I claim as new, and desire to secure by Letters Patent, is—

1. The method of recording articulate or other sound or sounds, which consists in setting up vibrations in a body, taking the vibrations from the body at several points or places, communicating them by independent conductors to a common point or place, and causing a record to be made from this common point or place.

2. The method of reproducing articulate or other sound or sounds, which consists in causing a record of vibrations to act at a single point or place and from this point or place communicating vibrations by independent conductors to several points on a vibratory body.

3. The method of recording and reproducing articulate or other sound or sounds, which consists in taking vibrations off a vibratory body at several points or places, communicating them to a common or central point or place by independent conductors, causing a record to be made from this common point or place, and then causing this record to act at the common or central point or place, communicating vibrations to a vibratory body at several points or places.

In testimony whereof I affix my signature in presence of two witnesses.

GIANNI BETTINI.
